(57) **CLAIM**

We claim the ornamental design for the toy ball with ropes,
as shown.

DESCRIPTION

FIG. 1 is a perspective view of the toy ball with ropes
showing our design;

FIG. 2 is a front end view thereof, the rear end view being
a mirror image;

FIG. 3 is a top plan view thereof in an alternative position,
the bottom plan view being a mirror image; and,

FIG. 4 is a right side elevation view of FIG. 2; the left side
elevation view being a mirror image.
